(57) **CLAIM**

The ornamental design for a vehicle wireless charger, as shown and described.

DESCRIPTION

FIG. 1 is a perspective view of the vehicle wireless charger showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of portions of the vehicle wireless charger is included for the purpose of illustrating environmental structure and forms no part of the claimed design.
